(57) **CLAIM**

The ornamental design for a bottle, as shown and described.

DESCRIPTION

FIG. 1 is a top, front, right side perspective view of a bottle;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof, shown at a reduced scale; and,

FIG. 7 is a bottom plan view thereof.

The broken lines shown on the bottom surface in FIG. 7 are included for the purpose of illustrating environmental structure and form no part of the claimed design.
